UNITED STATES PATENT OFFICE.

ELWIN H. KIDDER, OF CHICAGO, ILLINOIS, ASSIGNOR TO LINK-BELT COMPANY, OF CHICAGO, ILLINOIS, A CORPORATION OF ILLINOIS.

CLAMPING DEVICE FOR CAR UNLOADERS.

Application filed November 28, 1924. Serial No. 752,586.

My invention relates to improvements in clamping device for car unloaders and shows a clamping device which will operate automatically to clamp a car on the unloading frame when the frame or cradle rotates to dump the car. One object of my invention is to provide such a device as will be easily and conveniently operated, will be automatic in its operation and will always 5 exert a sufficient amount of power to insure proper functioning of the apparatus. Other objects of my invention will appear from time to time in the specification and claims.

15 My invention is illustrated more or less diagrammatically in the accompanying drawings, wherein—

Figure 1 is a side elevation of the unloader;

20 Figure 2 is a section along the line 2—2 of Figure 1 showing the clamp mechanism in elevation;

25 Figure 3 is a view similar to Figure 2 showing the unloader in partly rotating position with the clamp in operation;

Figure 4 is a detail view of the lifting carriage.

Like parts are indicated by like characters throughout the specification and drawings.

30 A is a cradle mounted on a plurality of ring frames A¹, which frames travel on rollers A² adapted to be rotated to rotate the ring frame and cradle by means of power applied through a drive shaft A³. A⁴ is a transfer table supported on rollers A⁵ A⁶ by means of inclined wedge blocks A⁶ A⁶ on the cradle. A⁷ A⁷ are car tracks on the transfer table adapted to support a car A⁸.

35 There may be two or more of the ring frames, depending on the length of the cradle and the length of the cars to be dumped thereby. Associated with each of these ring frames is an automatic clamping device which forms the subject matter of the present invention. This automatic clamping device is adapted to come down and grip the top of the car body and hold it on the tracks so that when the cradle is rotated and the car is turned upside down with the 40 dumping, the car will be held in place without leaving the rails. The clamping arrangement is the same for each ring frame and a description of one, of course, suffices for all.

45 B B¹ are guide tracks. Slidable on the

track B is a short jaw clamp B² and slideable on the track B¹ is a long jaw clamp B³. Associated with the bracket for one of the rollers A² is a stop bracket B⁴ adapted to be engaged by a lifting carriage B¹⁰ floating on the ring frame. B⁵ is a lifting rope extending from the lifting carriage B¹⁰ about sheaves B⁶ B⁷ at the bottom of the ring frame and B⁸ B⁹ at the top and terminating in an equalizer carriage B¹⁰. Extending 50 from the lever B¹¹ on the equalizer-carriage is the long clamp lifting rope B¹² which passes over a sheave B¹³ and a sheave B¹⁴ and is anchored on the long jaw clamp B³. B¹⁵ is a short jaw clamp lifting rope 55 extending from the end of the lever B¹¹ over a sheave B¹⁶ to the short jaw clamp B². Thus when the cradle is in the upright position, the lifting carriage will have engaged the stop bracket and will have been held against 60 further movement so as to draw out the lifting rope and lift both the long and short jaw clamp. When the cradle is rotated in a counter clockwise direction, the lifting carriage B⁵ will travel on its rollers B¹⁷ along 65 the track B¹⁸ toward the sheave B⁶ and permit the clamps to descend under the force of gravity until they engage or rest upon the top of the car, the parts being so positioned that this descent of the clamps and 70 their engagement with the car will have been completed before the cradle rotates far enough to unseat the car from the track rails on which it stands.

75 C is the clamp holding rope. It is anchored at one end on one end of a relieving spring C¹, and at the top to the short jaw clamp B², passes over a sheave C², sheave C³ to a sheave C⁴ on the equalizer sheave carriage C⁵, thence over a sheave C⁶ to an 80 equalizer spring C⁷ anchored on the long jaw clamp. The equalizer carriage C⁵, is 85 slideable in tracks C²⁶ and a rope C²⁷ leads from this carriage over a sheave C⁸ and is wound about a drum C⁹. C¹⁰ is a lowering 90 counterweight adapted to travel in the counterweight housing C¹¹. It is suspended by a counterweight rope C¹² passing over a sheave C¹³ and wound about the drum C⁹. C¹⁴ is a brake band wound about the drum 95 and adapted to be gripped upon the drum by means of the brake counterweight C¹⁵ on the counterweight lever C¹⁶. The purpose of this counterweight and drum is to 100 draw the holding rope tight when the rotation 105 of the cradle is stopped. C¹⁷ is a counterweight 110 lever.

tion of the cradle permits the clamps to descend, the arrangement being such that as the cradle rotates after the clamps have been drawn down against the top of the car, the counterweight will create a tension in the brake band and hold the drum against rotation, thus holding the clamps in a down position against the weight of the car when it turns over. The relieving springs permit a sufficient amount of play and resiliency to insure smooth operation and protect the apparatus from shock.

Referring to the lifting carriage B⁴⁰ shown in Figure 4, B⁴¹ is a friction shoe pivoted on the carriage and held against the track by the spring B⁴². The purpose of this is to frictionally hold the lifting carriage in place wherever it may be when the tension on the cable B⁵ is released as otherwise as the dump turns over this carriage might slide or drift and permit tangling of the cable. The tension is of course only sufficient to hold the carriage against movement when in the idle position.

It will be evident that while I have shown in my drawings an operative device, still many changes might be made in the size, shape and disposition of parts without departing materially from the spirit of my invention and I wish, therefore, that my showing be taken as in a sense diagrammatic.

The use and operation of my invention are as follows:

A gondola car to be dumped is run onto the tracks on the transfer table while the cradle and associated parts are in the upright position. The cradle is then rotated in a counter clockwise direction and the car and transfer table will move to the left through a limited excursion with respect to the cradle when it comes to rest against the side thereof. This rotation will continue with the lifting carriage remaining at rest with respect to the stop but moving in the cradle until the clamps have travelled down to engage the car as the sheave at the bottom of the ring frame approaches the stop carriage. This downward movement of the clamps will be assisted by the pull of the counterweight which winds up the holding rope on the drum so that this rope is taut at all times. As soon as the clamps settle down on the top of the car, they can move no further and the cradle will continue to rotate, and the holding rope will be held tight. Further rotation will cause the brake counterweight lever to rotate in a clock-wise direction about its pivot exerting a tension on the brake band. This tension will be exerted before the cradle has turned far enough to cause the weight of the car to be lifted from the rails and as the rotation continues the car will gradually turn over until practically its entire weight is carried by the clamps, the brake band holding the

drum against rotation. The parts remain in this position until the car has gone up far enough so that it can be dumped.

The car after being dumped will be returned by return movement of the cradle and as it moves back, first the brake lever will release the tension on the brake band and then the lifting carriage will engage its stop and a tension will be exerted on the clamp lifting ropes and the clamps will finally be raised to the top of the cradle drawing in on the brake drum and raising the counterweight freeing the car to permit its removal from the transfer table and lifting the cradle ready for the next dumping operation.

I claim:

1. In a rotary car dumper, a rotary car supporting cradle, a clamp adapted to hold a car thereon and clamp holding means comprising a drum, a cable leading from the clamp and wound about the drum, and a brake adapted to lock the drum.

2. In a rotary car dumper, a rotary car supporting cradle, a clamp adapted to hold a car thereon and clamp holding means comprising a drum, a cable leading from the clamp and wound about the drum, and a brake adapted to lock the drum as the cradle is moved to the dumping position.

3. In a rotary car dumper, a rotary car supporting cradle, a clamp adapted to hold a car thereon and clamp holding means comprising a drum, a cable leading from the clamp and wound about the drum, and a brake adapted to lock the drum, a weighted brake actuating lever pivoted on the cradle and adapted to lock the brake when the cradle is rotated a predetermined distance toward the dumping position.

4. In a rotary car dumper, a rotary car supporting cradle, a clamp adapted to hold a car thereon and clamp holding means comprising a drum, a cable leading from the clamp and wound about the drum, a counterweight cable wound about the drum, a counterweight carried thereby and adapted to rotate the drum to keep the clamp cable tight and a brake adapted to lock the drum.

5. In a rotary car dumper, a rotary car supporting cradle, a clamp adapted to hold a car thereon and clamp holding means comprising a drum, a cable leading from the clamp and wound about the drum, a counterweight cable wound about the drum, a counterweight carried thereby and adapted to rotate the drum to keep the clamp cable tight and a brake adapted to lock the drum as the cradle is moved to the dumping position.

6. In a rotary car dumper, a rotary car supporting cradle, a clamp adapted to hold a car thereon and clamp holding means comprising a drum, a cable leading from the clamp and wound about the drum, a coun-

terweight cable wound about the drum, a counterweight carried thereby and adapted to rotate the drum to keep the clamp cable tight and a brake adapted to lock the drum, 5 a weighted brake actuating lever pivoted on the cradle and adapted to lock the brake when the cradle is rotated a predetermined distance toward the dumping position.

7. In a rotary car dumper, a rotary car 10 supporting cradle, clamps adapted to hold a car thereon and clamp holding means comprising a cable anchored at each end on the clamps, sheaves over which the cable travels, a carriage supporting one of said 15 sheaves, a drum, a cable extending from said carriage and wound about the drum and a brake adapted to lock the drum.

8. In a rotary car dumper, a rotary car supporting cradle, clamps adapted to hold 20 a car thereon and clamp holding means comprising a cable anchored at each end on the clamps, sheaves over which the cable travels, a carriage supporting one of said 25 sheaves, a drum, a cable extending from said carriage and wound about the drum and a brake adapted to lock the drum as the cradle is moved to the dumping position.

9. In a rotary car dumper, a rotary car 30 supporting cradle, clamps adapted to hold a car thereon and clamp holding means comprising a cable anchored at each end on the clamps, sheaves over which the cable travels, a carriage supporting one of said 35 sheaves, a drum, a cable extending from said carriage and wound about the drum and a brake adapted to lock the drum, a weighted 40 brake actuating lever pivoted on the cradle and adapted to lock the brake when the cradle is rotated a predetermined distance toward the dumping position.

10. In a rotary car dumper, a rotary car supporting cradle, clamps adapted to hold 45 a car thereon and clamp holding means comprising a cable anchored at each end on the clamps, sheaves over which the cable travels, a carriage supporting one of said 50 sheaves, a drum, a cable extending from said carriage and wound about the drum and a brake adapted to lock the drum, a counterweight and a cable supporting it and 55 wound about the drum adapted to exert a tension on the clamp holding cable system.

11. In a rotary car dumper, a rotary car 60 supporting cradle, clamps adapted to hold a car thereon and clamp holding means comprising a cable anchored at each end on the clamps, sheaves over which the cable travels, a carriage supporting one of said 65 sheaves, a drum, a cable extending from said carriage and wound about the drum and a brake adapted to lock the drum as the cradle is moved to the dumping position, a counterweight and a cable supporting it and 70 wound about the drum adapted to exert a tension on the clamp holding cable system.

12. In a rotary car dumper, a rotary car supporting cradle, clamps adapted to hold a car thereon and clamp holding means comprising a cable anchored at each end on the clamps, sheaves over which the cable 75 travels, a carriage supporting one of said sheaves, a drum, a cable extending from said carriage and wound about the drum and a brake adapted to lock the drum, a weighted 80 brake actuating lever pivoted on the cradle and adapted to lock the brake when the cradle is rotated a predetermined distance toward the dumping position, a counterweight and a cable supporting it and wound about the drum adapted to exert a tension on the clamp holding cable system.

13. In a rotary car dumper, a rotary car supporting cradle, clamps adapted to move toward and from the car to hold it on the cradle, means for moving the clamps away 85 from the car comprising cables leading from each clamp, an equalizer lever to which said cables are attached, a lifting cable attached to the fulcrum of the lever and means associated therewith for pulling 90 it out to raise the clamps as the cradle approaches the upright position.

14. In a rotary car dumper, a rotary car supporting cradle, clamps adapted to move toward and from the car to hold it on the 95 cradle, means for moving the clamps away from the car comprising cables leading from each clamp, an equalizer lever, an equalizer carriage adapted to travel on the cradle and support the equalizer lever, a 100 lifting cable attached to the carriage and means associated therewith for pulling it out to raise the clamps as the cradle approaches the upright position.

15. In a rotary car dumper, a rotary car 105 supporting cradle, clamps adapted to move toward and from the car to hold it on the cradle, means for moving the clamps away from the car comprising cables leading from each clamp, an equalizer lever to which 110 said cables are attached, a lifting cable attached to the fulcrum of the lever and means associated therewith for pulling it out to raise the clamps as the cradle approaches the upright position, said means being adapted 115 to pay out the cable and lower the clamp as the cradle approaches the dumping position.

16. In a rotary car dumper, a rotary car 120 supporting cradle, clamps adapted to move toward and from the car to hold it on the cradle, means for moving the clamps away from the car comprising cables leading from each clamp, an equalizer lever to which said 125 cables are attached, a lifting cable attached to the fulcrum of the lever and means associated therewith for pulling it out to raise the clamps as the cradle approaches the upright position, said means comprising a carriage mounted for travel along the pe- 130

periphery of the cradle upon which the cable is anchored and a stop removed from the cradle in the path of the carriage.

17. In a rotary car dumper, a rotary car supporting cradle, clamps adapted to move toward and from the car to hold it on the cradle, means for moving the clamps away from the car comprising cables leading from each clamp, an equalizer lever to which said cables are attached, a lifting cable attached to the fulcrum of the lever and means associated therewith for pulling it out to raise the clamps as the cradle approaches the upright position, said means comprising a plurality of sheaves on the cradle over which the cable travels, tracks on the cradle, a carriage on which the cable is anchored adapted to travel along said tracks and a stop fixed alongside the path of the cradle and adapted to engage the carriage to stop its movement and cause it to move along the tracks along the cradle to draw out the cable as the carriage approaches the upright position.

18. In a rotary car dumper, a rotary car supporting cradle, a clamp adapted to hold a car thereon and clamp holding means comprising a drum, a cable leading from the clamp, wound about the drum, and a brake adapted to lock the drum, means for moving the clamp away from the car comprising a carriage and means associated therewith for pulling it out to raise the clamp as the cradle approaches the upright position.

19. In a rotary car dumper, a rotary car supporting cradle, a clamp adapted to hold a car thereon and clamp holding means comprising a drum, a cable leading from the clamp wound about the drum, and a brake adapted to lock the drum, means for moving the clamp away from the car comprising a carriage and means associated therewith for pulling it out to raise the clamp as the cradle approaches the upright position, a weighted brake actuating lever pivoted on the cradle and adapted to lock the brake when the cradle has rotated a predetermined distance toward the dumping position.

20. In a rotary car dumper, a rotary car supporting cradle, a clamp adapted to hold

a car thereon and clamp holding means comprising a drum, a cable leading from the clamp wound about the drum, and a brake adapted to lock the drum, means for moving the clamp away from the car comprising a carriage and means associated therewith for pulling it out to raise the clamp as the cradle approaches the upright position, a weighted brake actuating lever pivoted on the cradle and adapted to lock the brake when the cradle has rotated a predetermined distance toward the dumping position, and means comprising a counterweight and cable wound about the drum for exerting a tension on the other cables.

21. In a rotary car dumper, a rotary car supporting cradle, a clamp adapted to move toward and from a car and to hold it on the cradle, means for moving the clamp away from the car comprising a cable attached to the clamp and means associated with the cable for pulling it out to raise the clamp as the cradle approaches the upright position, said means comprising a carriage mounted for travel along the periphery of the cradle upon which the cradle is anchored and a stop removed from the cradle in the path of the carriage.

22. A car holding mechanism comprising; a rotatable cage adapted to contain a car to be dumped; a pair of hooks on said cage adapted to be moved from a raised position above a car body in said cage to a lowered position in engagement with said car body; mechanical equalizing means joining said hooks; and means for moving said hooks from their raised position to their lowered position, said hook lowering means adapted to be operated by rotation of said cage.

23. A car holding mechanism comprising a hook adapted to be moved from a raised position above a car body to a lowered position in engagement with a car body; means for moving the hook from its raised position to its lowered position; and means operated by gravity for positively clamping said hook in its lowered position.

Signed at Chicago county of Cook and State of Illinois, this 20th day of November 1924.

ELWIN H. KIDDER.
